UNITED STATES PATENT OFFICE.

STEPHEN PAVLOFF, OF CAMAS, WASHINGTON.

PRUNE GATHERER.

Application filed August 26, 1922. Serial No. 584,462.

To all whom it may concern:

Be it known that I, STEPHEN PAVLOFF, a citizen of the United States, residing at Camas, in the county of Clark and State of Washington, have invented a new and useful Prune Gatherer, of which the following is a specification.

My invention relates to improvements in prune gatherers in which a canvas hopper 10 on a hand truck is disposed under a prune tree.

The usual procedure in gathering prunes is first, to shake the prunes to the ground and then pick them up again and place them 15 in a box.

The objects of my invention are:

First, to furnish a mechanism which gathers the prunes en masse as they are shaken off the tree.

Second, to prevent the prunes from getting soiled by contact with the ground.

Third, to save the time wasted in gathering each individual prune.

Fourth, to construct a mechanism which 25 can be quickly set up or taken down, and which can easily be transported from one place to another.

Further objects and advantages are to be found in the construction and arrangement 30 of parts as will be described hereinafter in the specification and particularly pointed out in the appended claims:

I attain these objects with the mechanism illustrated in the accompanying drawing, in which:

Fig. 1 is a plan view of the entire mechanism.

Fig. 2 is a side view of Fig. 1.

Fig. 3 is a rear end view of Fig. 1.

Fig. 4 is a detail of an extensible supporting post with part of the canvas hopper attached thereto.

Fig. 5 shows in detail the manner of attaching the extensible supporting post to the frame.

Similar numerals refer to similar parts throughout the several views.

The wheels of the hand truck are designated by the numeral 1. Mounted on these 50 wheels is a frame 2 to which are attached the supporting posts 3. The manner of connecting the posts to the frame is illustrated in Fig. 5 where it is shown that the lower half of the hinge 4 is attached to the frame while to the upper half of the hinge as at 6 55 is pivotally mounted the supporting post 3.

On the upper half of the hinge is a curved slot 5 which throughout its extent is concentric to the pivotal point 6. A thumb screw 7, extending through slot and post, 60 enables the latter either to be secured in an upright position or if occasion requires to be swung against the frame 2 as shown by the dotted lines 3 in Fig. 5. The reason for employing a hinge 4 instead of a rigid 65 bracket is that the upright post can be swung farther outward when desired.

To increase the effective gathering area of my device each post is equipped with an extension leg 8 which is held in position by 70 means of the clamps 9 shown in Fig. 4 or by any other means suitable. The top of the extension leg should be equipped with a pulley 10; a cord 11 leads over the pulley, and this cord has at one end a hook which is 75 to be hooked into the rings 12 of the canvas hopper 13. The other end of the cord is fastened in any suitable way to the frame as shown at 14 in Fig. 4. The box 15 which is to contain the prunes is placed under the bottom orifice of the hopper and preferably so that the hand truck can be moved without disturbing the filled box.

One hand truck may, but two hand trucks 80 are preferably employed, one on each side of the tree and the adjoining edges of the canvas hopper are buttoned together as shown at 16 in Fig. 3 to form a collar around the trunk 17 of the tree. Such portion of the upper part of the canvas hopper as is not actually needed may be folded inwardly as indicated by the numeral 18 in Fig. 4.

After the gathering underneath one tree 85 is completed the two hoppers are separated from each other and the hand trucks are shifted to another tree either with or without dismantling the remaining hopper structure. If it is desired to transport the trucks 90 over a long distance, a horse may be put between the tongues 19 of the hand trucks, but in that case the hand trucks should be joined by a removable bridge 20 between the frames at the front and rear (see Fig. 3). Said bridge may consist simply of a staple 100 or of any other suitable device connecting the two frames.

Having thus described my invention, it 110 will be seen that my objects have been accomplished, and, though I have shown the preferred form of construction, I reserve to myself the right to make minor changes

providing I do not violate the spirit and principle of my invention.

I claim:

In a prune gatherer, the combination of a
5 canvas hopper, posts with extension legs
supporting the upper edge of the hopper, a
frame at the lower ends of the posts, a
hinge between said frame and each post, said
posts being pivotally connected to the upper

half of each hinge, a curved slot in the upper
10 half of each hinge said slot being concentric
to the pivotal point between post and hinge,
a thumb screw holding the posts to the hinge
at the desired position within the slot, and a
hand truck to support the frame.

Signed by me at Portland, Oregon, this
15 18th day of August, 1922.

STEPHEN PAVLOFF.
